UNITED STATES PATENT OFFICE.

LEROY J. LINDSAY, OF SEYMOUR, IOWA.

MARKER FOR PLANTERS.

953,849.

Specification of Letters Patent.

Patented Apr. 5, 1910.

Application filed June 26, 1909. Serial No. 504,511.

To all whom it may concern:

Be it known that I, LEROY J. LINDSAY, a citizen of the United States, residing at Seymour, in the county of Wayne and State of Iowa, have invented a certain new and useful Marker for Planters, of which the following is a specification.

My invention relates to that class of markers for planting devices in which two marker arms are provided on opposite sides of the machine frame and means are arranged for automatically moving them from marking position to an elevated position at rest, said means being actuated by the turning of the planter at the ends of the rows.

My object is to provide improved means of simple, durable, and inexpensive construction whereby each marker arm when moving to its elevated, inoperative position will be turned at such an angle that when its supporting chain is slackened, it will readily and easily move by gravity downwardly and outwardly toward the ground, and when it strikes the ground, it will then swing outwardly relative to the planter to the desired position for marking.

A further object is to provide an arm supporting device so arranged that when the planter is being transported from place to place without being operated, it may be manually turned to such a position that the forward end of the marker arm will rest upon a part of the planter and ordinary strains upon the pivotal joint of the marker arm will be thereby relieved.

My invention consists in the construction, arrangement, and combination of the various parts of the device whereby the objects contemplated are attained, as hereinafter more fully set forth, pointed out in my claims, and illustrated in the accompanying drawings, in which—

Figure 1 shows a top or plan view of a part of a planter frame with my improved marking device applied thereto. The dotted lines show the marker arms in operative and inoperative positions. Fig. 2 shows an enlarged, detail, side view of one of the marker arms. Fig. 3 shows a top or plan view of one end of the beam that supports the marker arm and the adjacent end of one of the marker arms connected therewith by means of my improved device, the portion of the marker arm being shown in its position at rest. Fig. 4 shows a like view illustrating the marker arm in its position for

use. Fig. 5 shows an end view of the beam for supporting the marker arm with a portion of the marker arm connected therewith by means of my improved device, said 60 marker arm being shown in position at rest. Fig. 6 shows a front view of one end of the beam for supporting the marker arm and a marker arm in position for use and my improved connecting device for the marker 65 arm. The dotted lines in said figure show the position that the marker arm assumes when at rest. Fig. 7 shows a sectional view on the line 7—7 of Fig. 6, it being assumed that the marker arm is in the position shown 70 by dotted lines in said figure. Fig. 8 shows a detail view illustrating the adjustable limiting stop for the chain, and Fig. 9 shows a detail perspective view illustrating the brackets that support the beam for the 75 marker arm.

Referring to the accompanying drawings, I have used the reference numeral 10 to indicate that portion of a planter shown. In order to attach my improvement to a 80 planter, it is necessary to provide two guide loops 11 at the forward corners thereof and a guide loop 12 on the tongue in line with the loops 11.

My improved marker attachment comprises a supporting beam 13 detachably connected with the rear of the planter frame by means of two brackets 14. On each end portion of said beam is a flat metal plate 15 arranged vertically on the front face of the 90 beam and having a shoulder 16 projected forwardly and arranged on an angle inclined downwardly and inwardly toward the center of the planter, as clearly shown in Fig. 6. This plate is also provided with a 95 round opening 17 adjacent to the flange 16.

The marker arm proper is supported upon a bolt, which bolt comprises a straight body portion 18 extended through the beam and through the plate 15 and then extended 100 downwardly at 19, and then rearwardly at 20, its end being provided with a rounded head 21. On the rear of the bolt are two locking nuts 22. The said bolt is so arranged that the rounded head 21 is yieldingly held toward the plate 15 and is capable in one position of its movement of entering the rounded opening 17 a short distance, as shown in Figs. 6 and 7, and said bolt head is also free to slide on the plate 15. Each 110 marker arm comprises a body portion 23 having, at its inner end, two plates 24 and

25, said plates being provided with openings to receive the bolt 19 to thereby pivotally connect the marker arm with the part 19 of the bolt. On the outer end of the 5 marker arm is a marker blade 26 of ordinary construction. There is also an eye-bolt 27 connected with the outer end of each marker arm. A chain 28 is attached at its ends to said eye-bolts 27 and is extended through 10 the loops 11 and 12. The chain is of such length that when one marker arm is in operative position substantially at right-angles to the longitudinal axis of the planter, the other marker arm will be in an inoperative 15 position substantially parallel with the longitudinal axis of the planter, as shown in Fig. 1.

In order to limit the movement of the marker arms relative to the loops 11, I have 20 provided an adjustable split washer 29, as shown in Fig. 8, which may be detachably connected with the chain 28 to thereby limit the movement of the marker arm by engaging with the adjacent loop 11. One of these 25 washers is placed on the chain near each marker arm to thereby limit the movement of the marker arm.

In practical use and assuming that the marker arms are in the position shown by 30 solid lines in Fig. 1, then it is obvious that as the planter is advanced across a field, the marker blade will form a furrow in the ground parallel with a line on which the planter is advanced. The resistance upon 35 the blade caused by frictional engagement with the ground is sufficient to apply such tension to the chain as to normally hold the other marker arm in an elevated position. Then, when turning around at the end of the 40 field, the planter is turned toward the marker arm that previously formed the furrow thus releasing the tension upon the chain and permitting the other marker arm to drop by gravity toward the ground. 45 Then, when the turning movement is completed, the other marker arm will swing outwardly to position substantially at right-angles to the planter and the first mentioned marker arm will be moved to an elevated position substantially parallel with 50 the planter.

It is desirable that when either marker arm moves from its position substantially parallel with the machine, it will move both 55 downwardly and outwardly whenever the tension on the supporting chain is released. In order to successfully accomplish this function, I have provided the structure illustrated for connecting the marker arm 60 with the supporting beam. The arrangement of the bolt, comprising the parts 18, 19, 20 and 21, is such that when the marker arm is in position for forming a furrow, the marking blade will be in a substantially 65 vertical position and will also be free to move

up and down to conform to the irregularities in the ground surface, and then as the marker arm swings forwardly and upwardly, it is desirable that it be turned on its pivot so that its pivotal point will be inclined downwardly and toward the longitudinal center of the planter so that there will be a tendency for the marker arm to swing downwardly and outwardly. This desirable result is accomplished by means of the structure shown for 70 the reason that when the marker arm is in position for use, the part 19 of the bolt will be inclined downwardly and in a slight degree toward the longitudinal center of the planter. Then as the marker arm swings 75 forwardly and upwardly, the weight on the outer end thereof will operate to slide the head 21 of the bolt upwardly and toward the opening 17, and when said head reaches the opening, it will be yieldingly held therein 80 and the marker arm will be held in such position that when the tension on the chain is released, it will swing downwardly and outwardly at such an angle as to insure its automatic operation by gravity as soon as the 85 tension on the chain is released.

The flange 16 serves to prevent the head 21 of the bolt from moving forwardly past the opening 17, and it also serves another desirable function as follows: Assuming 90 that the planter is to be transported without operation, then the operator may grasp each marker arm and turn it around to position with the head 21 of the bolt resting on top of the flange 16, and when in said position, the 100 forward end of the marker arm may rest upon the forward portion of the planter so that all strains upon the bolt that supports the marker arm will be relieved.

It is desirable that when the marker arm 105 is in position substantially parallel with the planter, that it be yieldingly held against pivotal movement relative to the supporting beam, as otherwise the part 19 of the bolt might assume a substantially vertical position on account of the shaking of the planter so that when the chain became slackened, the marker arm would fail to move by gravity 110 downwardly and outwardly.

I claim as my invention.

1. In a device of the class described, the combination of a supporting beam, a plate fixed to the supporting beam in an upright position, a device pivoted to the supporting beam and having frictional engagement with 120 said plate, a marker arm pivoted to said device and designed to rest upon the ground surface at its outer end, said parts being so arranged that, when the marker arm is moved to a forwardly extended position, it 125 will be frictionally held by said device in such position that its forward end will tend to move by gravity downwardly and outwardly when it is released, for the purposes stated.

2. In a device of the class described, the combination of a supporting beam, a plate fixed to it in an upright position, a bolt extended through the plate and beam in a substantially horizontal position, and then downwardly, and then toward the plate, and a marker arm pivoted to the downwardly extended portion of said bolt.
3. In a device of the class described, the combination of a supporting beam, a plate fixed to it in an upright position, a bolt extended through the plate and beam in a substantially horizontal position, and then downwardly, and then toward the plate, and a marker arm pivoted to the downwardly extended portion of said bolt, said plate being provided with an opening, and said bolt being provided with a rounded head to enter said opening, said opening being arranged relative to the plate and to the substantially horizontal portion of the bolt that when the head is in the opening, the substantially vertical portion of the bolt will extend downwardly and toward the central portion of the beam.
4. In a device of the class described, the combination of a supporting beam, a plate fixed to it in an upright position, a bolt extended through the plate and beam in a substantially horizontal position, and then downwardly, and then toward the plate, and a marker arm pivoted to the downwardly extended portion of said bolt, said plate being provided with an opening, and said bolt being provided with a rounded head to enter said opening, said opening being arranged relative to the plate and to the substantially

horizontal portion of the bolt that when the head is in the opening, the substantially vertical portion of the bolt will extend downwardly and toward the central portion of the beam, and a flange formed on said plate near its inner end, said bolt being capable of swinging to position adjacent to the inner side of said flange.

5. In a device of the class described, the combination of a planter frame, a beam fixed to the rear thereof, a device on each end of the beam comprising a plate fixed to the forward side of the beam and provided with a flange at its inner end extending downwardly and inwardly toward the longitudinal center of the planter, said plate also being provided with an opening adjacent to said flange, a bolt passed through the beam and the plate and extended downwardly in front of the plate and then rearwardly toward the plate and provided with a rounded head designed to partially enter said opening and to be capable of sliding on the plate, a marker arm pivoted to the downwardly extended portion of the bolt, a marker blade on the arm, a chain connected with the outer end of each marker arm, and means connected to the planter frame for slidingly supporting the chain relative to the frame, arranged and combined substantially in the manner set forth and for the purposes stated.
